UNITED STATES PATENT OFFICE.

NORMAN M. SWEET AND GEORGE KALIL SAWAYA, OF NASHVILLE,
TENNESSEE.

MAIL AND ORDER FILING SYSTEM.

No. 851,145.

Specification of Letters Patent.

Patented April 23, 1907.

Application filed November 26, 1906. Serial No. 345,266.

To all whom it may concern:

Be it known that we, NORMAN M. SWEET, residing at Nashville, in the county of Davidson and State of Tennessee, and GEORGE KALIL SAWAYA, residing at Nashville, in the county of Davidson and State of Tennessee, both citizens of the United States, have invented a certain new and useful Mail and Order Filing System, of which the following is a specification, reference being had therein to the accompanying drawings.

This invention relates to filing cabinets designed for filing and indexing mail matter such as letters and general correspondence and also orders, the object of the invention being to provide a cabinet well adapted to the purpose set forth, and further to provide means whereby letters and orders of any date or under any name may be quickly and securely located.

With the above and other objects in view, the nature of which will more fully appear as the description proceeds, the invention consists in the novel construction, combination and arrangement of parts, herein fully described, illustrated and claimed.

In the accompanying drawings;—Figure 1 is a perspective view of a filing cabinet constructed in accordance with the present invention, the partitions and cards being omitted therefrom. Fig. 2 is a vertical longitudinal section through the same, showing the movable partitions and cards in place therein, and letters or orders or the like filed away. Fig. 3 is a vertical transverse section through the cabinet. Fig. 4 is a side elevation of one of the partitions. Fig. 5 is a side elevation of one form of card, and Fig. 6 is a side elevation of another form of card.

The main body of the cabinet consists of a box or trough like holder of an suitable length, width and depth, adapted to contain letters or orders or the like arranged side by side. The said body is shown as comprising a bottom 1, sides 2, and ends 3, while the body, as a whole, is supported at a suitable elevation by a frame shown as embodying supporting legs 4, connected and braced by stringers 5. The cabinet body may, however, be supported in any desired manner, the means shown and described being convenient for all ordinary purposes.

In carrying out the present invention, the top edges of the cabinet sides 2 are provided at frequent intervals with notches 6 arranged

in oppositely alined pairs adapted to receive and hold the opposite extremities of the supporting rods of a number of movable partitions 7, each having one of said supporting rods 8 connected thereto. Each partition 7 is made of stout material such as sheet metal and under the preferred embodiment of this invention one edge of the partition is rolled over as shown at 9 to embrace and confine the supporting rod 8, while the length of the rod is such that the ends thereof project beyond the side edges of the partition so as to lie in the notches 6, as shown in Figs. 2 and 3. The width and depth or height of each partition is slightly less than the internal dimensions of the cabinet body or holder, so that by lifting a partition, the extremities of the supporting rod may be disengaged from the notches 6 allowing said partition to be moved along the cabinet to the desired point where the rod extremities may again be engaged with the notches 6, the partition being thus securely held from slipping and releasing papers which may be confined between it and an adjacent partition. Where the papers are to be arranged alphabetically, a sufficient number of partitions are provided to conform to the number of letters in the alphabet, and others additional thereto as may be found desirable. Each partition is further provided with an upstanding tab 10 upon which appears a letter of the alphabet or other designating character suitable to the use for which the cabinet is designed.

In addition to the movable partitions above described, division cards 11 are employed, of the same width practically as the partitions, and these cards are provided with upstanding tabs 12 adapted to receive the names of the correspondents or patrons, as indicated in Fig. 5. Preferably these division cards are made in two thicknesses, a thin card, for example, being used for a party having but little business or correspondence, and a relatively thick card for a party conducting a relatively large amount of business or correspondence. These cards are also arranged alphabetically between the movable partitions thus facilitating reference and accessibility to any desired name.

As the volume of letters or other papers increases, the partitions are shifted to accommodate them, and in order to keep the papers, cards and partitions in compact order, a movable stop or abutment block 13

of sufficient weight is arranged within the cabinet body, which stop or block backs up said parts, as shown in Fig. 2. The abutment face of the stop or block 13 is beveled or inclined, as shown, to permit the papers, cards and partitions to be spread apart at the top to give freer access to the papers, and at one end of the cabinet body is arranged another stationary block 14 with a correspondingly beveled or inclined surface having a like function. To separate one year's papers from those of a preceding or succeeding year, a card 15 of greater height is used, the same being placed between the last paper of one year and the first paper of the ensuing year, and by preference this card 15 is of some designating color, and is also provided with an upstanding tab 16, upon which the year appears.

20 In using the cabinet for filing orders, the cards 15 may be used to designate the different States or parts or sections of a country, the names of the States being placed on the tabs, as indicated in Fig. 6. These will be arranged alphabetically, while the intervening division cards 11 will have the names of different towns or cities in such States placed on the tabs thereof, and these will be arranged alphabetically to facilitate 25 ready reference thereto. Following the same plan or system, as above, a thin card may be used for a town where little business is done, and a relatively thick card may be used for a city where a relatively large 30 amount of business is conducted, all of which assists in enabling a person to quickly lay his hands upon any desired paper in the cabinet. The upwardly projecting tabs 10 of the movable partitions form convenient 35 finger pieces or grips which enable the operator to quickly shift said partitions, one after another, in getting at the papers desired, while the weight of said partitions insures their restoration to place and the positioning of the extremities of the supporting rods in the notches provided therefor in the 40 top edges of the cabinet sides.

We claim:—

1. A filing cabinet comprising a box-like body having notches along the top edges of 50 the sides thereof, and movable partitions embodying supporting rods adapted to rest in said notches.

2. A filing cabinet comprising a box-like body having notches in opposite relation 55 along the top edges of opposite sides thereof, and movable partitions supported by rods extending along the top edges thereof and projecting at their extremities beyond the 60 partitions and engaging said notches.

3. A filing cabinet comprising a box-like body having notches along the top edges of opposite sides thereof, and movable partitions with supporting rods extending along the top edges thereof and with tabs projecting 65 above said supporting rods for the purpose specified.

4. A filing cabinet comprising a box-like body having notches along the top edges of the opposite sides thereof, movable partitions 70 having supporting rods adapted to fit removably into said notches, and a movable back stop or abutment block adapted to be shifted along the body.

5. A filing cabinet comprising a box-like 75 body having notches along the top edges of opposite sides thereof, movable partitions having means to engage said notches, a stationary stop or abutment at one end of the body, and a movable stop or abutment within the body, said stops or abutments having beveled or inclined faces.

6. A filing cabinet comprising a box-like body, movable partitions adapted to be shifted along the body, means in line with 85 the tops of the partitions for retaining them in the places to which they are shifted, and intervening divisions cards interposed between the partitions.
